CLAIM

The ornamental design for a dust pan as shown and described.

DESCRIPTION

FIG. 1 is a top, front, right perspective view of the claimed design for a dust pan;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The uneven-length broken lines immediately adjacent to the shaded area are imaginary lines that depict boundaries of the claimed design and form no part thereof. The even-length broken lines showing the remainder of the dust pan depict environmental structure and form no part of the claimed design.
